DESIGN.

G. F. MEACHAM.

Casing Soda-Water Apparatus.

No. 6,366.

Patented Jan. 21, 1873.

Witnessed,

Geo. F. Meacham

Attest,

inventor,

Geo. F. Meacham

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR CASING OF SODA-WATER APPARATUS.

Specification forming part of Design No. 6,366, dated January 21, 1873.

To all whom it may concern:

Be it known that I, GEORGE F. MEACHAM, of Newton, in the county of Middlesex and State of Massachusetts, have invented and produced a new and original Design for the Casing of a Soda-Water Apparatus; of which the following is a full, clear, and exact description, reference being had to the accompanying photograph making part of this specification.

This invention consists in an ornamental design for the casing of a soda-water apparatus, whereby the lower or rectangular portion is relieved of its box-like appearance.

In the photograph, A represents the body or main portion of the casing of a soda-water apparatus, which is of rectangular form. Each corner of the portion A, at or near the center,

is cut away so as to form a notch, b, which thus relieves the rectangular portion of the apparatus of the box-like appearance which it would otherwise present, the design thus produced being unique and ornamental.

Claim.

What I claim as my invention, and desire to secure by Letters Patent, is—

The design of the portion A of the casing, substantially as herein shown and described.

Witness my hand this 31st day of December, A. D. 1872.

GEO. F. MEACHAM.

In presence of—

P. E. TESCHEMACHER,
G. A. MEACHAM.
